UNITED STATES PATENT OFFICE

164,481

CONTAINER FOR WICK-HOLDING BOTTLE

Ellis F. Ellis, Akron, Ohio, assignor to Coventry Ware, Inc., Barberton, Ohio, a corporation of Ohio

Application April 6, 1951, Serial No. 14,741

Term of patent 7 years

(Cl. D16—2)

To all whom it may concern:

Be it known that I, Ellis F. Ellis, a citizen of the United States, residing at Akron, State of Ohio, have invented a new, original, and ornamental Design for Container for Wick-Holding Bottle, of which the following is a specification, reference being had to the accompanying drawings, forming a part thereof. In the drawings the location of the wick-holding bottle is indicated in phantom lines and is not a part of the design.

Fig. 1 is a front elevational view of a container for a wick-holding bottle, showing my new design;

Fig. 2 is a view of the left side;

Fig. 3 is a top view;

Fig. 4 is a rear view;

Fig. 5 is a bottom view;

Fig. 6 is a view of the right side; and
Fig. 7 is a section on the line 7—7 of Fig. 4.

I claim:

The ornamental design for a container for a wick-holding bottle, as shown.

ELLIS F. ELLIS.
